United States Patent [19]

Feng

[11] Patent Number: Des. 310,468

[45] Date of Patent: ** Sep. 11, 1990

[54] INTEGRATED CIRCUIT INSERTION TOOL

[76] Inventor: Yee C. Feng, 5F-1, No. 189, Chang An E. Rd., Sec. 2, Taipei, Taiwan

[**] Term: 14 Years

[21] Appl. No.: 228,209

[22] Filed: Aug. 3, 1988

[52] U.S. Cl. D8/14; D8/52

[58] Field of Search D8/14, 51, 52; 29/206, 29/740, 741, 758, 764; 294/99.2; 81/3.8

CLAIM

The ornamental design for integrated circuit insertion tool, as shown and described.

DESCRIPTION

FIG. 1 is a perspective view of the integrated circuit insertion tool showing my new design;

FIG. 2 is a front elevational view thereof, the rear being identical;

FIG. 3 is a right side elevational view thereof, the left side being identical;

FIG. 4 is a top plan view thereof;

FIG. 5 is a bottom plan view thereof.

FIG. 3

FIG. 2

FIG. 1

FIG. 4
